(57) **CLAIM**

The ornamental design for an open shed attachment, as shown and described.

DESCRIPTION

FIG. 1 is a front perspective view of an open shed attachment showing my new design;

FIG. 2 is a front elevational view thereof;

FIG. 3 is a rear elevational view thereof;

FIG. 4 is a right side view thereof;

FIG. 5 is a left side view thereof;

FIG. 6 is top plan view thereof;

FIG. 7 is a bottom plan view thereof; and,

FIG. 8 is a front perspective view showing the open shed attachment mounted to a shed.

The broken lines are for illustrative purposes only and form no part of the claimed design.
